United States Patent Office.

EDWARD A. COOPER, OF BUFFALO, NEW YORK.

Letters Patent No. 79,107, dated June 23, 1868.

IMPROVED HARNESS-SNAP.

The Schedule referred to in these Letters Patent and making part of the same.

TO ALL WHOM IT MAY CONCERN:

Be it known that I, EDWARD A. COOPER, of the city of Buffalo, county of Erie, and State of New York, have invented a certain new and improved Harness-Snap; and I do hereby declare that the following is a full and exact description thereof, reference being had to the accompanying drawings, making a part of this specification, in which—

Figure I is a side elevation of my improved harness-snap, the two parts of which it is composed being shown separate.

Figure II is also a side elevation of the same, said parts being shown as connected.

Figure III is a top view of the same.

The nature of this invention consists—

First, in a hollow chamber, one side of which is formed by the main shank of the snap-hook, and the other side by the tongue thereof, and which chamber contains the spring.

Second, in hinging the tongue of the snap in the centre, and providing the rear end of the same with a lug, which projects into the said chamber, and against which the end of the spring rests.

Third, in a thumb-piece projecting sidewise from the extreme end of the tongue, in close proximity to the hook, for the purpose hereinafter described.

Letters of like name and kind refer to like parts in each of the figures.

A represents the hook, and A' the loop of my improved harness-snap. These parts are formed upon opposite ends of the main body B. A hollow chamber is formed between this part B and the tongue C, the latter being made in the shape of a flat plate, and fitting on to the side of the part B, like the cover of a box. A screw or rivet, d, passes through both parts B and C, connecting them together, and at the same time forming the fulcrum upon which the tongue oscillates.

E represents a flat metallic spring, which is placed within the hollow chamber, one end being secured to the part B in any convenient manner, and the other free end bent semicircular, and bearing against a lug, g, projecting from the part C. The location and operation of the spring may be reversed by connecting one end thereof to the part C, and forming the lug g upon the part B, but I prefer the first above described construction of my improved harness-snap.

It will be seen that the fulcrum of the tongue is located in the centre instead of one end thereof, by which means the tongue is made a two-armed lever, one arm closing the hook A and the other carrying the lug g, for the purpose above stated. The fulcrum being nearer the end of the tongue which closes the hook, gives that end a shorter and less movement, so that it can be removed from the end of the hook quicker than if the fulcrum were farther distant from the end. For the purpose of bending or operating the tongue C, I provide a thumb-piece, h, which projects sidewise from the extreme end of the tongue, as shown in Fig. II. By means of this thumb-piece, the operator is enabled to move the tongue entirely out of the way of the hook, without obstructing with his thumb the opening required for disengaging the snap-hook from the ring or other part of the harness to which it is attached.

The spring used in connection with a harness-snap of this construction may be of inferior quality than those to be found in other snap-hooks, and my improved construction renders this invention a more durable and convenient article, and superior to all the snap-hooks now in common use.

What I claim as my invention, and desire to secure by Letters Patent, is—

The arrangement, with the main body, of the hook constructed with a flat plate, and inwardly-projecting lug g, and an outwardly-projecting thumb-piece, h, and a flat spring, E, one end of which is secured to the lug, which receives the screw in the main body, and the other end bears against the lug g, and having an entirely closed chamber for the spring, as herein described.
